(57) **CLAIM**

The ornamental design for a trunk luggage, as shown and described.

DESCRIPTION

FIG. 1 is a front perspective view of a trunk luggage showing my new design;

FIG. 2 is a front view thereof;

FIG. 3 is back view thereof;

FIG. 4 is a right side view thereof;

FIG. 5 is a left side view thereof;

FIG. 6 is a top view thereof; and,

FIG. 7 is a bottom view thereof.

The shading in the drawings reflects areas of color or shading contrast and not particular colors or shadings, and forms no part of the claimed design.

The broken lines in the drawings and the whited out areas within the broken lines show portions of the trunk luggage that form no part of the claimed design.
